UNITED STATES PATENT OFFICE.

SAMUEL VEIT SWOBODA, OF CHEMNITZ, GERMANY.

STRETCHING-FRAME FOR EMBROIDERING SEWING-MACHINES.

No. 905,247.

Specification of Letters Patent.

Patented Dec. 1, 1908.

Application filed July 8, 1907. Serial No. 382,755.

To all whom it may concern:

Be it known that I, SAMUEL VEIT SWOBODA, a subject of the German Emperor, residing at Chemnitz, in the Kingdom of Saxony, in the Empire of Germany, have invented a new and useful Improvement in Stretching-Frames for Embroidering Sewing-Machines, of which the following is a specification.

10 My object is to provide an embroidering sewing machine with detachable means whereby finished hose can be ornamented with embroidered multi-color designs equal to handwork, and I attain this object by the adoption of a stretching block or frame to receive the hose or the like and moving same angularly and in an endwise direction under the needle of the machine in such a manner as to enable the embroidery to be 20 produced.

An embodiment of my invention is illustrated in the accompanying drawings, in which:

Figure 1, is a side-elevation of the main 25 portion of an embroidering machine fitted with my improved hose-stretcher, which is shown in section carrying a half hose; Fig. 2, is a front-elevation corresponding to Fig. 1.

The drawing shows a single needle machine of ordinary construction, which is fitted with the stretching frame. The latter consists of rings 1, 2, and 3 connected together by a longitudinal bar 4.

The sock 5 or the like is stretched over 35 the frame and preferably held in position

by means of split spring bands 6 and the whole is then placed upon the arm 9 of the machine as indicated. When the part of the sock where the embroidery is to be made has been placed in position under the machine-needle it will only be necessary to lower the presser-foot and work the machine. If it be necessary to carry the embroidery beyond the middle ring 2, either the latter may be moved along the bar 4, or 40 the sock may be unfastened at the ring 3 and pushed back to and secured on the ring 2. Thus, embroidery stitches can be made almost over the entire surface of finished hose. It will be understood that the shuttle box is 50 carried in the head of the arm 9 and is thereby lodged within the tubular hose. Further, in machines having a plurality of embroidery needles, each such needle will be provided with a similar stretching frame. 55

What I claim is:

In combination with the stitching mechanism of an embroidering machine, of a removable stretching frame for finished hose, composed of three successive metal annuli, 60 a longitudinal bar extending from an end with the extreme annuli, means for rigidly fixing the three annuli to the longitudinal bar, and a split ring surrounding each annulus as set forth.

SAMUEL VEIT SWOBODA.
